TYPEWRITER

Joseph Lee Sweeney, New York, N. Y.

Application April 25, 1938, Serial No. 204,225

17 Claims. (Cl. 197—45)

This invention relates to improvements in typewriters and more particularly to a typewriter of such character that speed and volume of work are of secondary importance but in which cost and educational value are of prime importance.

In accordance with my invention, all the functions of the usual key levers of a normal typewriter are reduced. The entire keyboard is on a single plate on which the normal key buttons are fastened in their normally correct position, so that a pressure on any button will type on the paper whatever type has been previously selected.

In my invention the particular type character selected is controlled by hand and the control mechanism includes a relatively long cylinder or roll extending across the machine inside the casing and position rearwardly of a long narrow slot or window. Such cylinder is operatively connected to a type wheel so that movement of the cylinder is in exact relation to movement of the type wheel.

In one form of the machine, I place a series of arrows in a helical or spiral form around the cylinder, so that any one moment there is only one full arrow displayed through the window or slot. Positioned adjacent the slot at the exterior of the casing, is a set of characters corresponding to the characters on the type wheel and arranged in a definite sequence, so that the arrows on the cylinder may be employed to select a particular type character which will be impressed against the paper when the keyboard is depressed.

Instead of arranging the arrows on the cylinder and the characters on a plate adjacent the slot, I may reverse this arrangement and place the characters on the cylinder and the arrows on the plate.

I also propose to use a shiftable arrow in place of the spiral series of arrows or characters and to actuate the arrow by a spiral groove arranged about the cylinder.

With the foregoing objects outlined and with other objects in view which will appear as the description proceeds, the invention consists in the novel features hereinafter described in detail, illustrated in the accompanying drawings and more particularly pointed out in the appended claims.

In the drawings:

Fig. 1 is a top plan view of my improved typewriter.

Fig. 2 is a bottom plan view.

Fig. 3 is a longitudinal vertical sectional view taken on the line 3—3 of Fig. 2.

Fig. 4 is a perspective view of a portion of the platen assembly.

Fig. 5 is an exploded perspective view of the same.

Fig. 6 is a top plan view partly broken away of 5 the escapement device.

Fig. 7 is a side elevation of the same partly broken away.

Fig. 8 is a longitudinal sectional view of the rear portion of the typewriter showing a part 10 of the rocking platform which supports the slid-able platen assembly.

Fig. 9 is a bottom plan view of the type wheel showing in horizontal section a portion of the means employed to guide the wheel vertically 15 and to lock it against rotation while printing.

Fig. 10 is a vertical sectional view taken on the line 10—10 of Fig. 9.

Fig. 11 is a sectional view of a detail taken on the line 11—11 of Fig. 10.

Fig. 12 is an enlarged side elevation of a portion of the periphery of the type wheel and showing upper and lower case characters.

Fig. 13 is a top plan view of the structure shown in Fig. 12.

Fig. 14 is a perspective view of a spring forming part of the type wheel locking means.

Fig. 15 is a detail showing the gearing for actuating the character or indicator wheel from the hand-operated shaft, the section of this figure 30 being taken on line 15—15 of Fig. 2.

Fig. 16 is an enlarged detail partly broken away of the stationary indicating plate or strip and the rotatable indicating wheel that is illustrated in Figs. 1 to 3 inclusive.

Fig. 17 is a similar view of another modification of the structure illustrated in Fig. 16, in which the stationary plate is provided with a series of pointers and the index wheel is provided with spirally arranged characters.

Fig. 18 is also a view like Fig. 16 but showing a further modification in which the stationary character plate cooperates with a laterally shift-able pointer actuated by a spiral groove in the index roll.

Fig. 19 is a plan view of a detail of the modification illustrated in Fig. 18.

Fig. 20 is a sectional view of this detail taken on the line 20—20 of Fig. 19.

Fig. 21 is a fragmentary enlarged plan view of the structure shown in Fig. 19.

Fig. 22 is a view similar to Fig. 6 of another modification of the escapement mechanism.

Fig. 23 is a top plan view partly broken away

of a modification of the inking mechanism for the type wheel.

Fig. 24 is a vertical sectional view of the same, partly in elevation and taken on line 24—24 of Fig. 23.

Fig. 25 is a top plan view partly in substantially horizontal section of another modification of the escapement mechanism, the section being taken on the line 25—25 of Fig. 27.

Fig. 26 is a substantially vertical sectional view of this mechanism, partly in elevation.

Fig. 27 is a vertical sectional view taken on the line 27—27 of Fig. 25.

Referring particularly to Figs. 1, 2 and 3, the internal frame or chassis 24 of the machine, is preferably formed of sheet metal and comprises side walls 25, a front wall 26, a rear wall 27 and a bridge 28.

A dummy keyboard 29, which is movable up and down and provided with false keys 30 having characters arranged identically the same way as a standard keyboard, is mounted on the front end portions 31 of levers 32 which have their medial portions pivotally mounted on a horizontal pin 33 that extends through a hollow sheet metal block 34 that forms a part of the chassis. The arms of each lever diverge upwardly from the pivot 33 and the rear arms 35 of such levers engage the platen assembly at the points 36 so that such assembly is shifted toward the type wheel 37 each time the dummy keyboard is depressed.

The type wheel has on its periphery a series of lower case characters 38 and a series of upper case characters 39, and as best illustrated in Figs. 9 and 10, the type wheel is mounted on the upper end of a vertical rotatable shaft 40 which extends downwardly through a disc 41, sleeves 42, a helical gear 43 and the top 44 of the mounting block 34. The shaft is keyed to the parts 42 and 43 but may be raised and lowered relatively to these parts to accommodate the use of either the upper case characters 38 or lower case characters 39.

The type wheel has a pair of depending pins 45 engaging notches 46 in the disc 41, the latter being fixed to the sleeve 42. Due to this construction, it is obvious that the type wheel can rotate with the disc and be raised or lowered for the purpose heretofore mentioned.

During the printing operation, it is essential to properly center the character to be used in the printing, and for this purpose the type wheel has a bottom gear ratchet disc 47 fixed thereto, and the teeth 48 of this disc cooperate with a pawl 49. The latter may consist of a pin, having its lower end portion resting on and extending through the top of the block 34 and its upper end extending into an annular groove 50 in the underside of the type wheel. The pawl is moved toward and away from the shaft 40, and in order to move it into locking position, I may employ a substantially inverted U-shaped wire spring member 51 (Fig. 14) having a head portion 52 to engage the pawl, and leg portions 53 removably anchored in a sleeve 54 (Fig. 3) carried by the arms 35 of the levers 32. With this construction, each time the keyboard is depressed to cause the platen 55 to move against the type wheel, the pawl-actuating member 51 will move the upper end of the pawl 49 into engagement with a notch of the ratchet wheel 47 with the result that the type wheel will be temporarily locked during the printing operation.

The type of the wheel 37 may be inked by any suitable means. For example (Fig. 1), an

inking band 56 may contact the type characters and be mounted on the guiding spools 57 rotatably supported by posts 58 mounted on the bridge 36 of the chassis. As best shown in Figs. 1 and 3, horizontal links 59 are pivotally mounted on one of the posts and support a rotatable tensioning spool 60. The lower one of the links is connected by a coil spring 61 to the bridge 36 to cause the tensioning roller to maintain the inking band in taut condition.

For the purpose of turning and setting the type wheel, the helical gear 43 meshes with a similar gear 62 that is fixed to a horizontal shaft 63 journaled in brackets 64 forming part of the chassis. The ends of the shaft 63 are provided with external handles or knobs 65 to permit the operator to effect turning of the type wheel. The shaft 63 not only effects turning of the type wheel but is employed to rotate an index cylinder or roll 66. This is accomplished, as shown in Figs. 2 and 15, by means of a gear 67 fixed to shaft 63, and a gear 68 fixed to the shaft 69 of the roll; the latter shaft being journaled in brackets 70 forming part of the chassis.

An auxiliary casing 74 is mounted on the main casing to facilitate access to the inking ribbon 56.

Between the keyboard 29 and the auxiliary casing 74, the main casing is provided with a narrow horizontal slot or window 75 of substantially the same length as the keyboard to permit the index roll 66 to be seen from the front of the machine. In Figs. 1, 2, 3 and 16, the roll is provided with a spirally arranged series of arrows 76 corresponding in number not only to the characters on the false keys 30 but also to the characters 77 on a stationary index plate 78 secured along one edge of the slot 75. As the characters 77 are arranged in identically the same relation as the characters on a standard keyboard, it will be appreciated that if the operator by turning one of the knobs 65 causes one of the arrows 76 to point to a particular character 77 of the index plate, that character will be printed when the dummy keyboard is depressed. Obviously this will facilitate the teaching of students of typewriting, so that they cannot only readily locate particular characters in the same places where they will be found on a standard keyboard, but may then exert pressure on the desired corresponding false key, and this will enable students to rapidly learn the touch system.

Instead of placing the characters on the stationary plate and the arrows on the index roll, such arrangement may be reversed as shown in Fig. 17, in which the characters 79 are spirally arranged on the roll 80, and a corresponding number of arrows 81 are positioned on the stationary plate 82.

Still another arrangement is shown in Fig. 18. In this embodiment, the characters 83 are positioned on the stationary plate 84, and the slot 85 is bound at one edge by a thin stationary plate 86 functioning as a guide for a slidable arrow 87 having a pin 88 extending into a spiral groove 89 formed in the periphery of the roll 90. Obviously when the roll is turned, the spiral groove will act on the pin 88 and cause the arrow to move along the slot 85 to bring the arrow into register with any one of the characters 83.

Of course, even if the arrow 87 should not be used, the peripheral groove 88 will be displayed through the window 85 and will cooperate with the characters 83 in selecting the type to be printed.

When the arrow 87, in Fig. 18, reaches either

end of the spiral groove, it cannot be moved further by turning the roll in the same direction, and therefore I provide means to prevent the roll 90 from turning too far in either direction. For example, as shown in Figs. 19 to 21 inclusive, the hand-operated shaft 91 is provided with a gear 92 which by means of an idle gear 93 actuates a gear 94 fixed to the grooved roll 90; and a disc 95, fixed to the shaft 91 has a finger 96 that is adapted to engage an abutment 97 mounted on one of the brackets 98 in which the shafts are fulcrumed. Obviously when the shaft 91 is turned in either direction the finger 96 will be brought into contact with the abutment 97, and this will stop further turning of the shaft in that direction.

For the purpose of moving the type wheel upwardly to print upper case characters, the lower end of the type wheel shaft 40 is arranged immediately above a horizontal plate portion 99 arranged at the rear junction of shift levers 100. These levers may be formed integral with one another and diverge forwardly from the plate portion 99. The medial portions of the levers are pivotally mounted on a horizontal pin 101 supported by brackets 102 forming part of the chassis. The forward ends of the levers are provided with shift keys 103 which are arranged in the opening 73 of the main casing.

Referring now to the platen and escapement mechanism, a substantially inverted U-shaped member 104 (Figs. 3 and 8) consists of a horizontal track 105 having legs 106 at its ends. Such legs are pivotally connected at 107 by bolts or the like to the sides of the chassis. Wire springs 108 have medial coil portions arranged about the bolts, and one end of each spring is hooked through one of the side walls of the chassis as shown at 109. The opposite end of each spring bears against a lug 110 forming part of the leg 106. These springs urge the track 105 rearwardly, and as such force is exerted against the rear arms 35 of the keyboard levers 31, obviously such springs normally maintain the keyboard in raised position.

The carriage of the platen is mounted on and slides along the track 105, and this carriage preferably consists of a base plate 111 (Fig. 5) having depending flanges 112 and 113 to embrace the front and rear edges of the track 105; the flange 113 being provided with rack teeth 114.

As best illustrated in Figs. 6 and 7, the track 105 is provided with a depending lug 115 engageable with and arranged between upstanding lugs 116 and 117 provided on the rockable escapement pawl 118. The latter is pivotally mounted at 119 on a platform 120 formed at the top of an inverted U-shaped member having legs 121. Such legs, as best shown in Fig. 3, are rockably mounted at their lower ends on a pin 122 that extends through the mounting block 134.

The pawl 118 has teeth 123 and 124 which cooperate with the rack teeth 114, and it will be understood that if the inverted U-shaped member 120, 121, is moved in a clockwise direction, the pawl 118 will be shifted by the finger 115 to a position to feed the carriage 111 one step toward the left, then if the U-shaped member is returned to normal position, the teeth 123, 124, will complete the movement of the carriage.

It will also be understood that if the inverted U-shaped member 120, 121, remains stationary, while the track 105 is shifted transversely, the finger 115 will cooperate with the fingers 116 and 117 to shift the carriage one step toward the left.

In order to move the inverted U-shaped mem-

ber in a clockwise direction (Fig. 3), the legs 121 have forwardly extending detents 125 which are engaged by the rear ends of shift levers 126. These levers are rockably mounted on the horizontal pin 33, and their forward ends carry a 5 shift bar 127.

Any suitable means may be employed to hold the inverted U-shaped member 120, 121, and the shift bar 127 in normal position. For example, coil springs 128 may have their rear ends connected to the legs 121 and their forward ends connected to the shaft 63.

Instead of employing the escapement mechanism shown in Figs. 6 and 7, I may use the one shown in Fig. 22. In this case the rockable member 118a which is pivotally mounted on the shiftable platform 120a may carry a pivoted pawl 130 which has only a single tooth to cooperate with the rack 114a. A coil spring 131 may be employed to urge the pawl toward the rack. Here 20 also the finger 115a which depends from the carriage track cooperates with upstanding lugs 116a and 117a mounted on the rockable member 118a. I prefer to use the form shown in Fig. 22, for in that case a single spring may be employed to 25 hold the inverted U-shaped member 120a as well as the pawl 130 in normal position.

To facilitate inexpensive manufacture, the platen assembly, as shown in Fig. 5, may include end cheek plates 135 provided at the ends of the 30 carriage base 111. Each end plate is provided with notches 136 and 137, and a slot 138. The shaft 139 of the platen extends through the notches 137.

A paper guide member 140 has end portions 35 141, which rest on the base 111 and have notches 142 to accommodate the platen shaft.

The paper rolls 143 which serve to clamp the paper to the platen, are mounted on rods 144 and 145, and the member or apron 140 is apertured as shown at 146 to accommodate the rolls of the rod 145.

Plates 147 are adapted to abut against the outer surfaces of the cheek plates 135 of the carriage, and each plate 147 has slots 148, 149 and 45 a notch 150. In assembling the parts the platen shaft 139 is dropped into the notches 142 of the cheek plates of the apron 140. Then the shaft is dropped into notches 137 of the cheek plates 135 of the carriage. Then the plates 147 may 50 be applied by causing the end portions of the shaft 139 to enter the notches 150. Afterwards the ends of the rod 144 may be inserted through the notches 136 of the cheek plates 135 and the slots 148 of the plates 147. Then the ends of 55 the rod 145 are inserted through the slots 138 and 149. Then a spacing ring 151 is placed on the left end of the rod 144, and a latch 152 is placed on the left end of the rod 145. It will be observed that the ends of the rods are provided 60 with annular grooves 153, 154, and consequently after the parts have been assembled, wire springs 155 may be employed at each end of the platen to secure the parts in position. This may be accomplished by hooking the end 156 into the groove 153 of the rod 144 and subsequently hooking the end portion 157 of the spring into the groove 154 of the rod 145.

For line spacing, a sheet metal gear 158 may 70 be arranged on one end of the platen shaft, and it will be noted that this gear has opposite notches 159 at its center to accommodate abutment fingers 160 projecting from opposite sides of the shaft 139. The teeth of this gear cooperate 75

with teeth 161 of the latch 152, which is pivotally mounted on the end of the rod 145. When the latch is in the position shown in Fig. 4, the gear 158 is locked against rotation, but if the latch is swung outwardly, by manipulation of its handle 162, the gear is free to rotate with the platen shaft. A resilient pawl member 163 is secured to the knob 164 (Fig. 5) so as to always turn with the shaft, and the pawl cooperates with the teeth of the gear 158. If the gear is locked against rotation by the latch 152, the pawl will ratchet or slide over the teeth of the gear, but when the latch is released, the pawl 163 will cause the gear to rotate with the shaft so that the platen may be turned to any desired degree for shifting the paper. The knobs 164 are secured to the ends of the platen shaft by means of screws 165, and in order to cause the shaft to turn with the knobs, each knob (Fig. 5a) has notches 164a to receive the abutment fingers 160 of the shaft.

In order to apprise the operator when the end of a line has been reached, the platen carriage (Fig. 1) is provided with a projecting arm 175 adapted to contact with an upwardly projecting arm 176 of a lever that extends up through a hole 177 in the bridge 36 of the chassis. The lower end of the lever (Fig. 2) forms a hammer 178 arranged to tap a bell 179 supported by a bracket 180 that depends from the bridge. Instead of employing the inking mechanism shown in Figs. 1 and 3, I may use the structure illustrated in Figs. 23 and 24. In this form of the invention the ratchet wheel 47a at the bottom of the type wheel 37a forms a support for a substantially U-shaped plate 181. The latter is preferably made of sheet metal and is shaped at its inner edge portion to provide pairs of upper and lower fingers 182, 183. There may be three pairs of these fingers and each pair acts to loosely grip or embrace the ratchet wheel so that the latter may readily turn while supporting the plate. The latter carries the spools 184 and 185, which guide the inking ribbon 186.

Any suitable means may be employed to center the plate 181; for example, substantially bow shape wire springs 187 may have their forward ends anchored in the casing of the machine as illustrated at 188, and their rear ends extending into small apertures 189 in the plate. These springs, of course, allow the inking mechanism to rise and descend with the type wheel to take care of upper and lower case characters.

In Figs. 25 to 27 inclusive, I have illustrated another embodiment of the escapement mechanism shown in Fig. 22.

In Figs. 25 to 27 inclusive, the platen carriage plate 114b slides along the track 105b of the inverted U-shaped member 104b. A lever 190 is pivotally suspended from the track by a pivot pin 191, and a pawl 192 is pivotally connected to and supported by the lever as shown at 193. The pawl has a tooth 194 adapted to engage the teeth of the rack 114b.

A U-shaped wire spring 195 is carried by the lever and pawl and has its ends connected to end portions of the lever and pawl for the purpose of normally urging the free end portion of the pawl away from the free end portion of the lever.

A lug 196 is fixed to and depends from the lever, and it cooperates with an abutment 197 that is fixed to a platform 120b arranged at the top of the inverted U-shaped rocking member 121b, corresponding to the part 121 in Figs. 3 and 7.

A substantially V-shaped spring 108b has one of its ends secured to the bridge 24b, and its other

end secured to the free end portion of the lever 190, and it tends to normally urge the lever in a clockwise direction about the pivot 191 and to hold the parts 104b and 121b in normal position, i. e., rearwardly of the platen.

A stationary pawl 198 is positioned on the platform and functions normally to engage the teeth of the rack member 114b to hold the carriage against movement.

In actuating this form of escapement, whenever the member 104b is moved forwardly during the printing operation to bring the platen into engagement with the type wheel, the platform 120b will remain stationary so that the abutment 197 will prevent the lug 196 from moving forwardly. Consequently the lever 190 will move in a clockwise direction and the pivot pin 193 will move in the same direction. As the spring 195 is at the same time urging the pawl 194 toward the rack, it will be understood that the pawl will thus be brought into position to engage a succeeding tooth of the rack and at the same time the rack will move out of engagement with the stationary pawl 198. Therefore, when the carriage and platen are again moved rearwardly away from the type wheel, the pawl 194 will engage said succeeding tooth of the rack and will function to advance the carriage one step, where it will be locked in position by the stationary pawl 198.

If spacing is to be accomplished without printing, for example, by depressing the spacing bar 127 (Fig. 3), this will cause the platform member 121b to travel rearwardly in a direction away from the type wheel, and consequently the abutment 197 will push rearwardly against the lug 196 so as to swing the lever 190 in a counterclockwise direction and cause the pivot pin 193 to travel in the same direction, with the result that the pawl 194 will be brought into position to engage a succeeding tooth. Then when the member 121 again moves forwardly to normal position, the pawl 194 will advance the carriage one step and the stationary pawl 198 will act to lock the carriage against movement.

In operation, the operator may thread the paper into the platen assembly in the usual way, and adjust the paper to the desired position by manipulating one or both of the knobs 164. He can then select the desired type character to be printed by turning one or both of the knobs 65. For example, if he desires to print the letter "f," he will turn the knob 65 until the proper arrow 16 registers with the "f" on the character plate 78. When the operator turns the knob 65 to select such character, the gearing 62, 43, causes turning of the type wheel 37 to bring the proper type character 39 into printing position. Then by depressing the keyboard 29, the rear arms 35 of the keyboard levers will cause shifting of the platen assembly forwardly so that the paper will be contacted with the portion of the inking ribbon which is between the platen and the selected type. Upon release of the keyboard, the springs 108 will act on the inverted U-shaped member 104 and return the platen assembly and the keyboard to normal position. Due to the forward and backward movement of the platen assembly, the escapement mechanism illustrated in Figs. 6 and 7 will act to move the platen carriage one step toward the left to bring the paper into proper position to be impressed by the next type character selected.

After writing a word, for example, when it is desired to space, the operator depresses the space bar 127. This causes the rear ends of the

5 levers 126 to rise and move the inverted U-shaped member, 121, in a clockwise direction and then the springs 128 come into play to restore the parts to proper position. Of course, such movement causes the escapement mechanism to shift the platen assembly toward the left, even though the keyboard is not depressed.

When it is necessary to use an upper case character, the operator after selecting the desired type 10 character, presses down on either one of the shift keys 103 to raise the type wheel, before pressing downwardly on the keyboard to move the platen into contact with the inking ribbon.

Further manipulation of the machine will be 15 readily understood by anyone familiar with type-writers.

It will be appreciated from the foregoing, that 20 I have provided a machine which may be inexpensively manufactured, and the parts of which may be readily assembled, as the construction is such that the major portion of the mechanism may be made of stamped sheet metal or the like, and the casing may be made of such metal or 25 may be cast of metal or molded from suitable plastics.

Furthermore, I have provided a machine which 30 will be attractive to children and/or students, not only on account of its close resemblance to conventional present day typewriters, but because the characters are so arranged as to facilitate selection 35 of characters to be typed as well as placement of the fingers upon the proper keys when using the touch system.

Many modifications may be made in the mechanism disclosed without departing from the spirit 40 of the invention as expressed in the claims.

What I claim and desire to secure by Letters Patent is:

1. A typewriter of the class described, comprising a movable type-carrying member, a rotatable indicating cylinder provided with a spirally arranged series of indicating characters on the periphery thereof and corresponding in number to the type characters on the type-carrying member, an elongated window arranged parallel to and in close proximity to the cylinder for displaying the type characters of the cylinder when the cylinder is rotated, a series of indicating characters arranged adjacent to the window and stationary relative to the cylinder, and manually operated means for simultaneously shifting the type-carrying member and for turning such cylinder, the indicating characters of the cylinder corresponding in appearance to the type characters on the type-carrying member.

2. A typewriter of the class described, comprising a movable type-carrying member, a casing, a rotatable indicating cylinder arranged in the casing and having spiral indicating means positioned about its periphery, an elongated window in the casing arranged parallel to and in close proximity to the cylinder for displaying said spiral indicating means, a series of stationary characters corresponding in appearance with the characters of the type-carrying member and arranged adjacent to said window in cooperative relation with said spiral indicating means, a rotatable handle arranged at one side of the casing, and means operatively connecting the handle to the type-carrying member and cylinder for simultaneously shifting the type-carrying member and for turning said cylinder.

3. In a typewriter of the character having a rotatable type carrying member, a platen member, and a dummy keyboard means operatively

connected with one of said members for moving one member toward the other upon depression of the keyboard means, the improvement which comprises a stationary series of indicating characters extending along the typewriter adjacent to one of the longitudinal edges of the keyboard means and corresponding in appearance with the characters on the type-carrying member, an indicating cylinder rotatable about an axis spaced from the axis of the type-carrying member and having spiral indicating means cooperating with said series of indicating characters to indicate the type character selected to be used in printing, and manually operated means for simultaneously rotating the type-carrying member and said cylinder.

4. In a typewriter of the character having a movable type-carrying member, a platen member, and a dummy keyboard operatively connected with one of the members for moving one member toward the other upon depression of the keyboard, the improvement which comprises indicating means including a series of indicating characters arranged adjacent to the rear edge of the dummy keyboard, an indicating cylinder having substantially spirally arranged indicating means, one of said indicating means corresponding in appearance with the type characters of the type-carrying member and cooperating with the other of said indicating means to indicate the type character selected to be printed, a handle, and means operatively connecting the handle to the type-carrying member and cylinder whereby movement of the handle will cause simultaneous shifting of the type-carrying member and turning of said cylinder.

5. A typewriter of the character described, comprising a movable type-carrying member, a rotatable indicating cylinder provided with a spirally arranged series of indicating characters corresponding in appearance with the type characters of the type-carrying member, a series of relatively stationary indicating means extending lengthwise of the cylinder, positioned in close proximity to the cylinder, and cooperating with the characters on the latter to indicate a type character selected to be printed, and manually operated means for simultaneously shifting the type-carrying member and for turning said cylinder.

6. In a typewriter of the character having a movable type-carrying member, a platen member, and a dummy keyboard operatively connected with one of the members for moving one member toward the other upon depression of the keyboard, the improvement which comprises a housing into which the keyboard is depressible, a set of indicating characters arranged on the housing and corresponding in appearance with the type characters on the type-carrying member, an elongated window in the housing, an indicator shiftable lengthwise of the window and cooperating with said set of indicating characters to indicate the desired type selected to be printed, a rotatable cylinder arranged in the housing for rotation about a stationary axis and having spiral means engaging said indicator to shift the latter along said set of indicating characters, and manually operated means for simultaneously shifting the type-carrying member, indicator and cylinder.

7. In a typewriting machine having a movable type-carrying member, a platen member, and a depressible dummy keyboard operatively connected with one of the members for moving one member toward the other upon depression

- of the keyboard, the improvement which comprises a series of indicating characters forming part of the machine and corresponding in appearance with the type characters on the type-carrying member, a rotatable indicating cylinder having spirally arranged means cooperating with said series of indicating characters to indicate a type character selected to be printed, and manually operated means for simultaneously shifting the type-carrying member and for turning said cylinder.
8. In a typewriter of the character having a casing, a movable type-carrying member, a platen member, and a dummy keyboard operatively connected with one of the members for moving one member toward the other upon depression of the keyboard, the improvement which comprises a rotatable indicating cylinder arranged in the casing between the platen and keyboard and provided with a spirally arranged series of indicating characters, an elongated window at the front of the casing arranged parallel with the cylinder and positioned in close proximity to the latter to allow the indicating characters on the cylinder to be seen through the window, a series of relatively stationary indicating characters mounted on the casing adjacent to and extending lengthwise of the window, one of the series of indicating characters corresponding in appearance to the type characters of the type-carrying member and cooperating with the other series of indicating characters to indicate a type character selected to be printed, and manually operated means for simultaneously shifting the type-carrying member and for turning said cylinder.
9. A typewriter of the class described, comprising a movable type-carrying member, a rotatable indicating cylinder provided with a spirally arranged series of indicating characters on the periphery thereof, and corresponding in number to the type characters on the type-carrying member, an elongated window arranged parallel to and in close proximity to the cylinder for displaying the indicating characters on the cylinder, a second series of relatively stationary indicating characters arranged adjacent to and lengthwise of the window, one series of said indicating characters corresponding in appearance to the type characters on the type-carrying member, and manually operated means for simultaneously shifting the type-carrying member and for turning said cylinder.
10. A typewriter of the class described, comprising a movable type-carrying member, a rotatable indicating cylinder provided with a spirally arranged series of indicating characters on the periphery thereof and corresponding in number to the type characters on the type-carrying member, an elongated window arranged parallel to and in close proximity to the cylinder for displaying the characters on the cylinder when the cylinder is rotated, a second series of relatively stationary indicating characters, corresponding in appearance to the type characters on the type-carrying member and arranged adjacent to the window, and manually operated means for simultaneously shifting the type-carrying member and for turning such cylinder.
11. In a typewriter machine having a movable type-carrying member, a platen member, and a dummy keyboard operatively connected with one of the members for moving one member toward the other upon depression of the keyboard, a series of relatively stationary indicating characters corresponding in number and appearance with the type characters on the type-carrying member, a rotatable cylinder arranged adjacent to one of the longitudinal edges of the keyboard and including spirally arranged means positioned adjacent to and cooperating with said series of indicating characters to indicate a type character selected to be printed, and manually operated means for simultaneously shifting the type-carrying member and for turning said cylinder.
12. In a typewriter machine having a movable type-carrying member, a platen member, and a dummy keyboard operatively connected with one of the members for moving one member toward the other upon depression of the keyboard, the improvement which comprises a housing, a rotatable cylinder arranged in the housing between the platen and keyboard for rotation about a stationary axis and having a spiral peripheral groove, a guide slot arranged in the housing parallel with the rear edge of the keyboard and in close proximity to the cylinder, a pointer shiftable along said slot and extending into said groove, a relatively stationary set of indicating characters arranged on the housing adjacent to the guide slot and corresponding in appearance with the type characters of the type-carrying member, the pointer being movable along said slot to indicate the type character selected to be printed, and manually operated means for simultaneously shifting the type-carrying member and for turning said cylinder.
13. In a typewriter of the character having a rotatable type wheel member provided with a series of peripherally arranged type characters, a platen roll member arranged rearwardly of said wheel member, and a dummy keyboard operatively connected with one of the members for moving one member toward the other upon depression of the keyboard, the improvement which comprises a casing, an elongated window in the casing arranged parallel to one of the longitudinal edges of the keyboard and positioned between the platen and the keyboard, a rotatable cylinder arranged in the casing parallel to the window and having spiral indicating means arranged about its periphery and visible through said window, a relatively stationary set of indicating means arranged adjacent to said window, one of said indicating means corresponding in appearance with the type characters of the type wheel member and cooperating with the other of said indicating means to indicate the type character selected to be printed, and manually operated means for simultaneously rotating the type wheel member and said cylinder.
14. In a typewriter of the character having a rotatable type wheel member provided with a series of peripherally arranged type characters, a platen roll member arranged rearwardly of said wheel member, and a dummy keyboard operatively connected with one of the members for moving one member toward the other upon depression of the keyboard, the improvement which comprises a casing, an elongated window in the casing arranged parallel to one of the longitudinal edges of the keyboard and positioned between the platen and the keyboard, a rotatable indicating cylinder arranged in the casing parallel to the window and having spiral indicating means arranged about its periphery and visible through said window, a relatively stationary set of indicating means arranged adjacent to said window, one of said indicating means corresponding in appearance with the type characters of the type

wheel member and cooperating with the other of said indicating means to indicate the type character selected to be printed, manually operated means for simultaneously rotating the type wheel member and said cylinder, and means for limiting the turning movement of the cylinder.

5. In a typewriter of the character having a movable type-carrying element, a platen element, and a dummy keyboard operatively connected with one of said elements for moving one element toward the other upon depression of the keyboard, the improvement which comprises a housing member into which the keyboard can descend, an elongated window in the housing member between the platen member and keyboard, a rotatable cylindrical member arranged in the housing member in position to be seen through the window, one of said members being provided with indicating means corresponding in

10 appearance with the type characters on the type-carrying element, and the other member having indicating means arranged to cooperate with the first-mentioned indicating means to indicate the type character selected to be printed, one of said

15 indicating means including spiral means positioned about the periphery of the cylindrical member, a handle arranged at one side of the housing member, and means operatively connecting the handle to the cylinder member and type-carrying element for simultaneously shifting the

20 cylinder member and type-carrying element.

16. In a typewriter of the character having a movable type-carrying element, a platen element, and a dummy keyboard operatively connected

25 with one of said elements for moving one element toward the other upon depression of the keyboard, the improvement which comprises a housing member having a window, a rotatable cylindrical member arranged in the housing member, one of said members being provided with indicating means corresponding in appearance with the type characters on the type-carrying element, and the other member having indicating means arranged to cooperate with the first-mentioned indicating means to indicate the type character selected to be printed, one of said

30 indicating means including spiral means positioned about the periphery of the cylindrical member, and manually operable means for simultaneously shifting said cylindrical member to indicate a selected character and for shifting the type-carrying element to bring the selected type character into printing position.

17. In a typewriter of the character having a movable type-carrying element, a platen element, and a dummy keyboard operatively connected

35 with one of said elements for moving one element toward the other upon depression of the keyboard, the improvement which comprises a housing member into which the keyboard can descend, an elongated window in the housing member be-

40 tween the platen member and keyboard, a rotatable cylindrical member arranged in the housing member in position to be seen through the window, one of said members being provided with indicating means corresponding in appearance with the type characters on the type-carrying element, and the other member having indicating means arranged to cooperate with the first-mentioned indicating means to indicate the type character selected to be printed, one of said indicating means including spiral means positioned about the periphery of the cylindrical member and visible through said window, and manually operable means for simultaneously turning said cylindrical member to indicate a selected character and for shifting the type-carrying element to bring the selected type character into printing position.

ble cylindrical member arranged in the housing member in position to be seen through the window, one of said members being provided with indicating means corresponding in appearance with the type characters on the type-carrying element, and the other member having indicating means arranged to cooperate with the first-mentioned indicating means to indicate the type character selected to be printed, one of said indicating means including spiral means positioned about the periphery of the cylindrical member, a handle arranged at one side of the housing member, and means operatively connecting the handle to the cylinder member and type-carrying element for simultaneously shifting the

10 cylinder member and type-carrying element.

15. In a typewriter of the character having a movable type-carrying element, a platen element, and a dummy keyboard means operatively connected with one of said elements for moving one element toward the other upon depression of the keyboard means, the improvement which comprises a housing member having a window, a rotatable cylindrical member arranged in the housing member, one of said members being provided with indicating means corresponding in appearance with the type characters on the type-carrying element, and the other member having indicating means arranged to cooperate with the first-mentioned indicating means to indicate the type character selected to be printed, one of said

20 indicating means including spiral means positioned about the periphery of the cylindrical member and visible through said window, and manually operable means for simultaneously turning said cylindrical member to indicate a selected character and for shifting the type-carrying element to bring the selected type character into printing position.
